Inventor:

Willy Krebs
UNITED STATES PATENT OFFICE

WILLY KREBS, OF NIEDERLOSSNITZ, NEAR DRESDEN, GERMANY

INSERTION SOLE FOR BOOTS AND SHOES

Application filed October 12, 1927, Serial No. 225,799, and in Germany October 16, 1926.

Many persons suffer from complaints due to standing and walking specially older persons as the heavy body strongly loads the feet. When this complaint is neglected, chronical 53 deformations are caused, as for instance fallen arches.

This invention has for its object to provide an insertion-sole, constructed in accordance with orthopædic-points of view.

10 Insertion-soles are permanently used by a great number of people. It is a great convenience, when the insertion-sole is adapted to prevent the formation of the above mentioned complaints.

15 The insertion-soles, according to the invention are cheaper than specially constructed supporting insertions and they are more comfortable in wear than such special supporting insertions. A special advantage of the insertion sole is, that the orthopædic-elements of the sole are interchangeable.

The invention is illustrated, by way of example, in the accompanying drawing.

Fig. 1 is a top-plan view.

25 Fig. 2 is a side elevation and

Fig. 3 is a section.

The insertion-sole is of the same shape as the commonly used insertion soles. It consists of several layers, for instance four, there 30 may however be used any other number of layers. The two outer layers *a*, the lower one and the upper one, are somewhat thicker than the two inner layers *b*. The four layers are not connected by stitching all round as usual. 35 The stitch-seam *c* extends along one whole side, from the toe and the heel towards the shank portion on the other side and is then bent inward to join the other side farther on. The layers are not stitched together at the portion B of the sole, so that at this place 40 three open pockets are formed between the layers.

Although the inner layers *b* may be of the same size as the upper and lower layers, it is 45 advisable to give to the same the size of the portion B and of a stitching edge.

These pockets are designed to receive insertions of special type. The lower pocket is designed for an insertion *d* of hard material, for instance sheet-steel, horn, galalite or

the like. This insertion *d* is of such profile that it is adapted to the hollow of the foot and supports the same. Into the second or middle pocket an insertion *e* of cork or similar material is inserted which adapts itself 55 automatically to the profile of the lower insertion *d* and forms so to say an equalizing layer. The insertion *f* in the upper pocket is of soft material, for instance felt, to form a comfortable support for the sensitive plant 60 of the foot. The insertions *d*, *e* and *f* are removable so that the orthopædic-profile can be adapted to the shape and to the conditions of the foot.

The succession of the insertions may be altered or the one or other insertion may be omitted or the curvature may be increased by additional insertions or the supporting points may be otherwise distributed.

The insertion-sole might be used without 70 any insertions. The pockets might be arranged at any other part than the portion B or at the portion B and at any other point.

On the lower layer *a* a flap *g* is sewn along the outer edge of the portion B and designed 75 to close the free ends of the pockets and to prevent slipping out of the insertions.

I claim:—

An insertion sole for supporting fallen arches, comprising in combination with the 80 insertion sole proper composed of several layers sewn together with the exception of a certain portion at one side so that at this portion pockets open at one side are formed, a curved metal spring removably and adjustably inserted in the lower pocket, an insert of 85 elastic material softer than the metal spring removably mounted in the middle pocket, and an insert of soft material removably mounted in the upper pocket. 90

In testimony whereof I affix my signature.

WILLY KREBS.
